(57) **CLAIM**

The ornamental design for a luminaire, as shown and described.

DESCRIPTION

FIG. 1 is front perspective view of the luminaire of the present invention;

FIG. 2 is a top view of the design of the present invention;
FIG. 3 is a bottom view of the design of the present invention;
FIG. 4 is a front view of the design of the present invention.
The rear view is a mirror image of the front view, so the rear view is not depicted.

FIG. 5 is a right side view of the design of the present invention; and,

FIG. 6 is a left side view of the design of the present invention.
The broken lines shown on the drawings depict environment only and form no part of the claimed design.

The transparent surfaces feature diagonal shading which depict the proper curvature of the transparent surface represented.
